UNITED STATES PATENT OFFICE.

GEORGE F. HANDLEY, OF BROOKLYN, NEW YORK, ASSIGNOR TO ROYAL TYPEWRITER COMPANY, INC., OF NEW YORK, N. Y., A CORPORATION OF NEW YORK.

CARRIAGE-CONTROLLING MEANS.

1,277,719.

Specification of Letters Patent.

Patented Sept. 3, 1918.

Application filed October 27, 1917. Serial No. 198,773.

To all whom it may concern:

Be it known that I, GEORGE F. HANDLEY, a citizen of the United States, and a resident of the borough of Brooklyn, in the city of 5 New York, county of Kings, and State of New York, have invented certain new and useful Improvements in Carriage-Controlling Means, of which the following is a specification.

10 The present invention relates generally to typewriting machines and has more particularly reference to carriage controlling means such as are utilized in connection with tabulator stop mechanisms.

15 The main object of this invention is to re-arrange the elements associated with the transversely movable carriage in such a manner that a lighter and more compact structure and a better balancing of the carriage 20 may be obtained.

One feature of the invention resides in the rearrangement of the parts whereby the tabular stop bar is located in a plane between the usual carriage release mechanism 25 and tabular stop block together with means for actuating both the carriage release mechanism and the tabular stop block. In the preferred embodiment of the invention here shown, the carriage release mechanism includes a pivotally mounted rack releasing 30 lever and the tabular stop block is pivotally supported on the rear wall of the main frame in a plane back of the tabular bar together with means intermediate the rack 35 releasing lever and the tabular stop block which, when actuated by the tabulator key, will tilt the carriage feed rack rearwardly out of engagement with the escapement pinion and will at the same time tilt the tabular 40 stop block forwardly to co-act with the tabular rod.

Another feature of the invention resides in the provision of a brake element mounted independently of the carriage and which 45 moves in the same direction as the tabular stop block to effect braking engagement with the carriage. In the preferred embodiment here shown, the braking element is pivotally supported on the stop block and rests with 50 its free end on the escapement frame of the machine, said escapement frame being movable with the carriage for case shifting purposes but not transversely therewith. When the tabular block moves forwardly to co-act

with the stop bar the brake element slides 55 over the escapement frame into engagement with a member transversely movable with the carriage.

Other features of construction will appear 60 as the specification proceeds.

In the accompanying drawings the invention is embodied in a concrete and preferred form in which—

Figure 1 is a vertical longitudinal sectional view through the framework of a 65 typewriting machine showing the carriage and its associated elements, but with most of the parts comprising the machine omitted.

Fig. 2 is a top plan view of the elements associated with the carriage shown in Fig. 1, 70 the parts being broken away and in section to more clearly illustrate the device.

Fig. 3 shows a front elevation of the tabular stop block and actuating means therefor together with the brake element carried 75 thereby.

Fig. 4 is a fragmentary view, more or less diagrammatic in character, of the top of the tabular bar showing the co-action of the stop block with a stop on the bar.

Fig. 5 is a sectional view taken generally 80 on the irregular line 5—5, of Fig. 7, and looking in the direction of the arrows.

Fig. 6 is an enlarged view of the parts shown in the upper right hand corner of 85 Fig. 1 with the carriage in its lower case shift position, with the carriage feed rack out of engagement with the escapement pinion, with the stop block in engagement with a stop on the tabular bar and with the brake 90 element in engagement with the carriage.

Fig. 7 is a view similar to Fig. 6 with the carriage in its upper case shift position and with the parts in normal position.

1 indicates the main frame having the 95 rear wall 2 showing a part of the well-known Royal typewriter. 3 indicates the transversely movable carriage of conventional construction and provided with the usual case shift mechanism indicated by the member 4. 5 indicates the race way whereby the transverse shift of the carriage is effected. 6 indicates the escapement frame which has a rising and falling motion with the case shift mechanism in the usual way but is 100 mounted in a well-known manner so as not to partake of the traverse of the carriage.

Suitable carriage escapement and release

mechanisms are utilized, in the present instance taking the following form;—

7 is an escapement pinion mounted in the escapement frame 6 with which engages a carriage feed rack 8 suitably supported on a transverse bar or rail 9 provided with rearward extensions 10 pivotally mounted at 11 in the carriage frame 3, the carriage feed rack being normally held in engagement 10 with the escapement pinion by means of springs 12. 60 indicates an eccentrically adjustable stop, carried by the carriage frame 3, which projects over one of the extensions 10 to limit the upward movement of the 15 member 9. 13 is a rack releasing lever pivotally supported at 14 on the escapement frame and having a forwardly projecting member 15 that engages underneath the transverse extending member 9 to lift the 20 carriage feed rack upwardly out of engagement with the escapement pinion when said rack releasing lever 13 is tilted rearwardly on its pivot 14. 16 is a pad carried by the rack releasing lever at the point where it engages with the transverse member 9 and may 25 act as a braking element, sufficient pressure being obtained by the abutment stop 60 on the extension 10. 17 is a downwardly projecting extension from the rack releasing lever. 18 is a tabular bar of any suitable construction adapted to receive in any letter space position a tabular stop such as 19. The tabular stop block 20 is here shown in the form of a lever pivoted on the frame 35 work at 21 and having a downwardly projecting extension 22. Normally, a spring 23 urges the tabular stop block into the position shown in Figs. 1 and 7, that is, out of engagement with the stops carried on the tabular bar. It will be noted that the tabular bar is in a plane between the carriage escapement and the tabular stop block. 24 is a braking element, here taking the form of a lever loosely pivoted on stop block 20, having its 40 free end 25 resting loosely on the escapement frame 6 and provided with a pad or braking surface 26 adjacent to a carriage connecting rod 27. In order to adjust the braking element 24 so as to position it properly with 45 respect to connecting rod 27, a pivot 28 on which said braking element 24 is mounted has an eccentric portion 29 that extends into the tabular stop block 20, the parts being normally clamped in the position to which 50 they may be adjusted by means of a binding screw 30. It will be understood that by loosening said screw 30, the member 24 may be adjusted so that it will assume a proper position with relation to the carriage rod 27. 55 Suitable actuating means for the carriage release mechanism, the tabular stop block and the braking element carried thereby are provided which in the present instance take the following form: 31 is a tabulator key 60 pivotally supported in the frame work at

32 in any suitable manner and normally urged into the position shown in Fig. 1 by a spring 40. This tabulator key has a vertical arm 33 from which extends a link 34 that connects with the underside of arm 35 mounted on the rock shaft 36 suitably supported in the frame by means of ears 37. At the other end of this rock shaft 36 there is a lever 38 which is in a plane between the downwardly projecting extension 17 of the rack releasing lever and the downwardly projecting extension 22 of the tabular stop block. It will be understood that when the tabulator key 31 is depressed, the vertical arm 33 is moved forwardly pulling the link 34 with it and imparting a clockwise turning movement to the rock shaft 36, thereby causing the lower end of the lever 38 to engage with the extension 17 and the upper end of 38 to engage with the extension 22. This action causes the rack releasing lever 13 to be tilted rearwardly on its pivot 14 thereby lifting the carriage feed rack 8 out of engagement with escapement pinion 7 by the engagement of pad 16 with the underside of the transverse member 9, causing the rearwardly extending projections 10 to swing around their pivots 11 against the action of spring 12. At the same time the lower extension 22 of stop block 20 is moved rearwardly thereby tilting the stop block itself forward into the plane of stop 19 carried on tabular bar 18, so as to arrest the carriage after it has moved transversely a predetermined distance. The forward tilting of the stop block 20 causes the braking member 24 to turn on its pivot 28, thereby sliding its free end 25 on the escapement frame 6 and thus moving into engagement with the carriage rod 27 so that when the carriage release mechanism is actuated brake member 24 immediately applies the brake surface 26 to rod 27 to retard the transverse movement of the carriage so that stop block 20 will not strike with undue force against the tabular stop. It will be further understood that it is immaterial whether or not the carriage is in its upper case shift position since the escapement frame 6 moves vertically with the carriage and thereby lifts the braking element 24 with it so that the brake will be applied regardless of whether or not the carriage occupies the lower case position shown in Fig. 6 or the upper case position shown in Fig. 7.

I claim:

1. Carriage controlling means comprising: a main frame, a carriage transversely movable with respect to said frame, a carriage escapement and release mechanism, a tabular stop block mounted in an upright position at the rear center of the main frame on a pivot intermediate its upper and lower ends, a tabular stop bar in a plane between

the escapement mechanism and the stop block, and actuating means for the carriage release mechanism and the tabular stop block.

- 5 2. Carriage controlling means comprising: a main frame, a carriage transversely movable with respect to said frame, carriage escapement and release mechanism, a tabular stop block mounted in an upright position at the rear center of the main frame on a pivot intermediate its upper and lower ends, a tabular stop bar in a plane between the escapement mechanism and the stop block, and actuating means for tilting the 10 carriage release mechanism rearwardly and for moving the tabular stop block forwardly toward the tabular stop bar.

- 15 3. Carriage controlling means comprising: a main frame, a carriage transversely movable with respect to said frame, carriage escapement and release mechanism including a pivotally supported rack releasing lever, a pivotally supported tabular stop block, a tabular stop bar in a plane between the escapement mechanism and the stop block, pivotally supported means intermediate the rack releasing lever and the tabular stop block for rocking them in opposite directions to tilt the rack releasing lever 20 rearwardly and the tabular stop block forwardly, and means for actuating said intermediate means.

- 25 4. Carriage controlling means comprising: a main frame, a carriage transversely movable with respect to said frame, carriage escapement and release mechanism, a tabular stop bar, a tabular stop block mounted in an upright position at the rear center of the main frame on a pivot intermediate its upper and lower ends, actuating 30 means for the carriage release mechanism and tabular stop block, and a braking member mounted on the stop block and engaging with a portion of the carriage when the tabular stop block co-acts with the stop bar.

- 35 5. Carriage controlling means comprising: a main frame, a carriage transversely movable with respect to said frame, carriage escapement and release mechanism, a tabular stop bar, a tabular stop block pivotally mounted in an upright position at the rear center of the main frame on a pivot intermediate its upper and lower ends, a pivotally mounted brake element, and means 40 for moving both the tabular stop block and brake element in the same direction to effect braking and stopping of the carriage when the carriage release mechanism is operated.

- 45 6. Carriage controlling means comprising: a main frame, a carriage transversely movable with respect to said frame, carriage escapement and release mechanism, a tabular stop bar, a tabular stop block mounted in an upright position at the rear

center of the main frame on a pivot intermediate its upper and lower ends in rear of said stop bar, a braking element in rear of the carriage release mechanism, and means for moving both the stop block and the braking element forwardly to brake and stop the carriage when the carriage release mechanism is operated.

7. Carriage controlling means comprising: a main frame, a carriage transversely movable with respect to said frame and having a lifting and lowering movement for case shifting, an escapement frame vertically movable with the carriage but independent of the transverse movement thereof, carriage escapement and release mechanism, a tabular stop bar on the carriage, a tabular stop block mounted in the main frame for co-acting with the stop bar, a brake element pivotally supported independently of the carriage and having one end resting upon the escapement frame, and means for moving the tabular stop block toward the stop bar and the braking element against a member transversely movable with the carriage when the carriage release mechanism is actuated.

8. Carriage controlling means comprising: a main frame, a carriage transversely movable with respect to said frame and having a lifting and lowering movement for case shifting, an escapement frame vertically movable with the carriage but independent of the transverse movement thereof, a carriage escapement and release mechanism, a tabular stop bar, a tabular stop block pivotally supported on the main frame in rear of said stop bar, a braking element pivoted loosely on the stop block and having its free end resting upon the escapement frame, and means for rocking said stop block to co-act with the stop bar thereby causing the brake element to slide on the escapement frame into engagement with a member transversely movable with the carriage when the carriage release mechanism is actuated.

9. Carriage controlling means comprising: a main frame, a carriage transversely movable with respect to said frame and having a lifting and lowering movement for case shifting, an escapement frame vertically movable with the carriage but independent of the transverse movement thereof, a carriage escapement and release mechanism, a tabular stop bar, a tabular stop block pivotally supported on the main frame in rear of said stop bar, a braking element pivoted loosely on the stop block and having its free end resting upon the escapement frame, an eccentric adjusting means between the stop block and the brake element, and means for rocking said stop block to co-act with the stop bar thereby causing the brake element to slide on the escapement 13

frame into engagement with a member transversely movable with the carriage when the carriage release mechanism is actuated.

10. Carriage controlling means comprising: a main frame, a carriage transversely movable with respect to said frame, carriage escapement and release mechanism including a braking element, a tabular stop bar, a tabular stop block, actuating means

10 for the carriage release mechanism and

tabular stop block, and a second braking member mounted on the stop block and engaging with a portion of the carriage when the tabular stop block co-acts with the stop bar.

Signed at New York, in the county of New York and State of New York, this 25th day of October, 1917.

15
GEORGE F. HANDLEY.
